FIG. 1

FIG. 2

FIG. 4

FIG. 3

FIGURE 1 is a front view in elevation of a stringed instrument showing my new design;

FIGURE 2 is a back view in elevation thereof;

FIGURE 3 is a fragmentary view in cross-section taken on the line 3—3 of FIGURE 1, showing the solid body and the decorative openings which pass entirely through from front to back; and

FIGURE 4 is a view in perspective thereof showing the decorative openings which pass entirely through the body.

The dominant features of my new design are shown in solid lines in the drawing.

I claim:

The ornamental design for a stringed instrument, as shown and described.
